United States Patent Office

Des. 176,017
Patented Nov. 8, 1955

176,017

VISUAL SIGNALING DEVICE

Dewey O. Hayes, Independence, and Everett Robbins,
Kansas City, Mo.

Application June 8, 1954, Serial No. 30,865

Term of patent 14 years

(Cl. D72—1)

Fig. 1 is a front elevational view of a visual signaling device showing my new design,

Fig. 2 is a side elevational view thereof,

Fig. 3 is a top plan view thereof, and

Fig. 4 is an inverted plan view thereof.

We claim:

The ornamental design for a visual signaling device, as shown.
